(57) **CLAIM**

The ornamental design for an electrical housing with clock and outlets, as shown and described.

DESCRIPTION

FIG. 1 is a perspective view of an electrical housing with clock and outlets in accordance with the present disclosure. FIG. 2 is a front elevation view of the electrical housing with clock and outlets shown in FIG. 1;

FIG. 3 is a rear elevation view of the electrical housing with clock and outlets shown in FIG. 1;

FIG. 4 is a right side elevation view of the electrical housing with clock and outlets shown in FIG. 1;

FIG. 5 is a left side elevation view of the electrical housing with clock and outlets shown in FIG. 1;

FIG. 6 is a top plan view of the electrical housing with clock and outlets shown in FIG. 1; and,

FIG. 7 is a bottom view of the electrical housing with clock and outlets shown in FIG. 1.

In the drawings, the broken lines depict unclaimed subject matter only and form no part of the claimed design.
